UNITED STATES PATENT OFFICE

173,024

HOUSING FOR A DICTATING MACHINE

Gordon W. Florian, Fairfield, Conn., assignor to
Dictaphone Corporation, Bridgeport, Conn., a
corporation of New York

Application December 21, 1953, Serial No. 28,158

Term of patent 14 years

(Cl. D26—14)

To all whom it may concern:

Be it known that I, Gordon W. Florian, a citizen of the United States, residing in Fairfield, in the county of Fairfield and in the State of Connecticut, have invented a new, original, and ornamental Design for a Housing for a Dictating Machine, of which the following is the specification, reference being had to the accompanying drawing, forming part thereof.

Figure 1 is a perspective view of the front and one side of a housing for a dictating machine showing my new design; and

Figure 2 is a perspective view of the rear and the opposite side thereof.

The dominant features of my design reside in the portions shown in the full lines in the drawing.

I claim:

The ornamental design for a housing for a dictating machine, substantially as shown and described.
